ABSTRACT OF THE DISCLOSURE

A lamp bracket assembly is mounted on an aquarium lamp reflector. The lamp assembly comprises a lamp socket, a switch and a bracket. The bracket has a collar against which the switch abuts and a pair of shoulders adjacent the collar. A leg depends from each shoulder and the lamp socket is affixed to the legs at the end opposite from the shoulders. The bracket is connected from an electrically non-conductive substance and insulates the socket from any surrounding conductive substances.

BACKGROUND OF THE INVENTION**Field of the invention**

This invention relates to a lamp bracket assembly adaptable for use with a reflector utilized to dissipate light over an aquarium wherein the lamp socket is effectively insulated from surrounding metallic substances by the bracket member. More particularly, this invention relates to such bracket assembly provided with a lamp switch mounted exteriorly of the reflector and on the other side of the metallic shield from the lamp.

Discussion of the prior art

Aquarium lamps provided with lamp light reflectors have been used for many years. Prior art reflectors were provided with a standard lamp light on the interior of the reflector assembly operably using standard household alternating current. A switch was provided to turn the lamp "on" and "off." This switch was actuatable using a knob mounted exteriorly of the reflector but the switch mechanism per se was on the interior of the reflector facing the aquarium water. A metallic bracket was used which connected the switch with the lamp socket. That assembly was affixed to the metallic reflector.

This assembly has several different attendant disadvantages. Due to the fact that the switch mechanism per se with its metallic parts which conduct electricity were positioned facing the water, some normal vaporization of the water caused by, *inter alia*, the heat of the lamp, causes corrosion of these vital parts. This is so, since no protective covering against moisture intrusion is provided. Additionally, replacement of a switch or examination of the same is complicated because the switch actuating means is positioned on one side of the reflector, while the switch per se is positioned on the other. Hence, it became advantageous to provide an aquarium reflector assembly which obviated the disadvantages of these prior art assemblies. It became particularly desirable to provide a bracket assembly which insulated the socket member from surrounding conductive substances.

SUMMARY OF THE INVENTION**Objects of the invention**

It is an object of this invention, therefore, to provide a lamp bracket assembly useful in conjunction with an aquarium lamp reflector wherein the socket is insulated from surrounding conductive substances.

It is another object of this invention, therefore, to provide such a bracket assembly wherein the switch actuating

2

ing means and switch per se are on the same side of the reflector member, namely, exteriorly thereof.

These and other objects and advantages will become apparent from the following complete description, accompanying drawings and appended claims.

STATEMENT OF THE INVENTION

Broadly, this invention contemplates a lamp bracket assembly adaptable for use with an aquarium lamp reflector, said assembly comprising a lamp socket, a switch and a bracket comprising a collar against which said switch abuts and a pair of shoulders adjacent said collar and having depending from each shoulder a leg, said lamp socket affixed to said legs at the end opposite from said shoulders, said bracket constructed of an electrically non-conductive substance whereby said bracket insulates said socket from any surrounding conductive substances.

BRIEF DESCRIPTION OF THE DRAWINGS

The present invention can be more readily understood and appreciated by reference to the accompanying drawings, in which

FIG. 1 is a perspective view of the reflector assembly of this invention;

FIG. 2 is a sectional view taken along the line 2—2 of FIG. 1;

FIG. 3 is a sectional view taken along the line 3—3 of FIG. 2;

FIG. 4 is a sectional view taken along the line 4—4 of FIG. 2 showing a bracket joining the lamp with the switch through the reflector and serving as a moisture protection barrier or guard;

FIG. 5 is a sectional view taken along the line 5—5 of FIG. 4;

FIG. 6 is a perspective view of the protective bracket shown in assembly in other views;

FIG. 7 is a view of the exteriorly mounted switch partially broken away to reveal the contacts of the switch, and

FIG. 8 is a sectional view taken along the line 8—8 of FIG. 7.

DESCRIPTION OF PREFERRED EMBODIMENTS

A preferred embodiment of this invention is illustrated in the accompanying drawings which show the bracket assembly of this invention mounted on an aquarium lamp reflector. The bracket assembly comprises a switch 4 in the form of a knob housing its contacts therein which are brought into contacting relationship by revolution of the knob. Knob 4 is mounted against a collar portion of bracket 16 which collar portion comprises a pair of concentric circular rings 18 and 20 defining a groove 22. The entire collar is of such a size as to be passed through a suitable aperture in the reflector 6. Ring 18 of bracket 16 defines aperture 24 which accommodates wires 25 and 27 leading from switch 4 to socket assembly 30.

The bracket 16 has tapering legs 32 and 34 depending from the shoulders adjacent the collar which legs are integral with feet 36 and 38 having openings 40 and 42 employed to mount the socket assembly thereto as shown in FIG. 2. On its bottom, it has support ridges 50 and 52 running down a portion of legs 32 and 34 and on either side of ring 18 as shown by numerals 56 and 58 affixed to base 60 comprising the shoulders. Parallel running edges 62 and 64 function to reinforce cross-piece 70.

The bracket 16 is made of an electrically non-conductive material suitably an electrical insulating plastic material. It can be made of a hydrophobic material suitably a hydrophobic plastic material such as polyethylene, polyvinyl chloride, nylon and the like. It can be molded in one piece to provide an integral piece which can join the socket assembly including the switch to the reflector so that the

socket assembly portion to which the lamps are eventually connected is insulated from surrounding metallic conductive substances particularly from the metallic reflector shield 6.

The switch 4 generally comprises a rotary upper member 90 and a stationary lower member 92. Upper member 90 has a side which generally covers the major portion of lower member 92. Affixed to the top of upper member 90 is a pair of resilient spiraling conductive contacts A, each spiraling for about $\frac{1}{2}$ revolution and positioned on either sides of the rotary upper member 90 within the same. The lower member 92 comprises four beveled slots, one of which and a portion of another are visible in FIG. 7. Along the beveled portion of two of these four beveled slots are contacts B which in turn are connected to the wires 25 and 27 leading to the lamp assembly. Intermediate contacts B are non-conductive slots. In operation, the upper member is revolved so that the two resilient contacts pass over a non-conductive edge as 94 in FIG. 7 and thence pass down onto contacts B on beveled edge 96 adjacent slot 98. At the same time, contact is made with the other contact B on the other side of the switch in precisely the same manner. Further, revolution of member 90 removes the contacts A and positions them against a non-conductive surface 94 turning the lamp "off." The "off" position of the contacts is shown in FIG. 8. The two A contacts at the origin of their respective spirals are in contact with one another permanently.

The unitary bracket assembly comprising the bracket, switch and socket assembly is affixed to a suitable metallic reflector by inserting the switch and collar member through an aperture in the reflector and thus positioning the non-conductive shoulders of bracket 16 against the reflector shield 6. The legs 32 and 34 depend therefrom and hold socket assembly 30 away from reflector shield 16. The unitary insulating bracket assembly is firmly affixed to reflector shield 6 by virtue of fasteners 8 and 10 passing through apertures 12 and 14 of bracket 16. These fasteners can be plastic pins which lock the bracket against the reflector by virtue of a resilient end member which expands on the inside of the bracket after the same has passed through the apertures in the reflector shield 6 and in the bracket 16.

From the foregoing, it is apparent that the assembly of the instant invention solves the problems attendant with prior art lamp assemblies. It is apparent that the socket assembly is insulated from the reflector by virtue of the bracket means. Additionally, in a preferred embodiment, the actuating means for the switch and the switch per se are on the same side of the reflector thereby removing the switch from the water. Thus, the present assembly is devoid of the problems accompanying prior art reflector assemblies, particularly those employing conductive brackets and the like.

The terms and expressions used herein are terms of description and not of limitation as there is no intention in the use of such terms and expressions of excluding any equivalents, or portions thereof, as many modifications and departures are possible within the scope of the invention claimed.

What is claimed is:

1. A lamp bracket assembly adaptable for use with an aquarium lamp reflector, said assembly comprising a lamp socket, a switch and a bracket comprising a collar against which said switch abuts and a pair of shoulders adjacent said collar and having depending from each shoulder a leg, said lamp socket affixed to said legs at the end opposite from said shoulders, means for electrically connecting said switch to said lamp socket, and said bracket constructed of an electrically non-conductive substance whereby said bracket insulates said socket from any surrounding conductive substances.

2. A lamp bracket assembly according to claim 1, wherein said bracket is constructed of a molded plastic electrical insulating material.

3. A lamp bracket assembly according to claim 2, wherein said switch comprises a rotatable knob housing the contacts of said switch whereby rotation of said knob regulates the position of said contacts and said switch abuts said collar away from said lamp socket.

4. A lamp bracket assembly according to claim 3, wherein said collar comprises a pair of concentric rings extending outwardly from said shoulders and adaptable to be positioned through an aperture of a reflector shield.

5. A lamp bracket assembly according to claim 4, wherein said legs and said shoulders are reinforced by reinforcing members extending along at least a portion of said legs and said shoulders.

6. A lamp bracket assembly according to claim 4, wherein the inner ring defines an aperture for accommodating wires from said switch to said socket assembly.
